UNITED STATES PATENT OFFICE.

JAMES T. SMITH, OF BALTIMORE, MARYLAND.

BOILER.

SPECIFICATION forming part of Letters Patent No. 399,941, dated March 19, 1889.

Application filed November 22, 1888. Serial No. 291,611. (No model.)

To all whom it may concern:

Be it known that I, JAMES T. SMITH, of the city of Baltimore and State of Maryland, have invented certain Improvements in Vertical Water-Tube Boilers, of which the following is a specification.

In the description of the said invention which follows reference is made to the accompanying drawings, forming a part hereof, and in which—

Figure 1 is an exterior side elevation of the improved boiler with a portion of the outer shell thereof removed, and Fig. 2 a central vertical section of the same. Fig. 3 is a cross-section of the improved boiler, taken on the dotted line $x x$, Fig. 2. Figs. 4 and 5 are detail views of couplings for securing the tubes, on an enlarged scale.

Similar letters of reference indicate similar parts in all the figures.

In the said drawings, A represents the outer shell of the boiler, which is cylindrical and provided with a spherical head.

B is a cylindrical fire-box secured at its lower end to the shell by means of the leg C. The crown of the fire-box is spherical in shape, and is preferably cast of steel. In the center of the crown of the fire-box is a hole having a flange, a, to which is riveted the upper and open end of the cylindrical heater D. The lower end of this heater is spherical in form and situated below the grate-bars E.

F F are water-tubes which connect the side of the heater at a point above the grate-bars with the crown of the fire-box. In order to admit of this connection, the tubes F are curved at the lower end, as shown in Fig. 2. The ends of the water-tubes are threaded, and attached to the heater and crown of the fire-box by means of nuts c, hereinafter described.

By referring to Figs. 4 and 5, which respectively show an upper and a lower end of a water-tube and the parts of the boiler adjoining them, it will be seen that the heater side

and the crown of the fire-box are bored out to 45 a size considerably larger than the outside of the tube, and the connection completed by means of the two nuts c, one on each side of the sheet. These nuts are provided with inner projections, d, which approach each other 50 and are tightened on a washer made of some compressible material adapted to resist considerable heat, such as wood or paper. By this means the connection between the tubes and the boiler proper is rendered water-tight. 55

In view of the spherical shape of the crown-sheet of the fire-box, I provide the same at such points or places as receive the tubes F with an upper and a lower boss, respectively denoted by g and h, the faces of which are 60 parallel with each other.

G G are straight tubes arranged radially around the heater D to connect the heater with the water-space between the fire-box and the outer shell below the grate-bars. The 65 water in these tubes being cooler than that in the curved ones, a complete circulation of water through the boiler in the direction indicated by the arrows is maintained.

H is a smoke-pipe extending from the fire-box head through the spherical top of the shell. The boiler is provided with fire-doors of the usual kind, and also with a stand, J, which may be of any desirable construction.

I claim as my invention—
75
In a vertical cylindrical boiler, a centrally-placed fire-box having a heater dependent from its crown, combined with a series of water-tubes which connect the side of the said heater with the crown of the fire-box, and an 80 other series of water-tubes which unite the lower end of the said heater with the water-space around the said fire-box, substantially as and for the purpose specified.

JAMES T. SMITH.
